UNITED STATES PATENT OFFICE.

PATRICK MIHAN, OF CHELSEA, MASSACHUSETTS.

VENTILATOR FOR SHIPS.

SPECIFICATION forming part of Letters Patent No. 269,583, dated December 26, 1882.

Application filed April 14, 1882. (No model.)

To all whom it may concern:

Be it known that I, PATRICK MIHAN, of Chelsea, in the county of Suffolk, of the State of Massachusetts, have invented a new and useful Improvement in Ventilators; and I do hereby declare the same to be described in the following specification and represented in the accompanying drawings, of which—

Figure 1 is a front elevation, and Fig. 2 a vertical and transverse section, of a ventilator containing my invention, the nature of which is defined in the claims hereinafter presented.

In carrying out my invention, I have combined with a ventilator-hood having a mouth an internal partition and two hinged deflectors, and means of effecting the closing of the upper one of such deflectors when a sea may enter with force the mouth of the hood, the object of thus closing the upper deflector being to prevent the water from being drawn upward within the hood and over the top of the partition, and thence falling down through the hood or part thereof in rear of the partition.

In such drawings, A is the ventilator-hood, having on one side of it a mouth, a, of a square or other suitable form, and also having within and across it the said hood, and in rear of and arranged, as represented, with the mouth, a partition, b.

In the hood are the two deflectors B and C, the lower one of them—viz., that marked C—being hinged at its upper part to the lower part of the partition b. The upper deflector, B, is hinged to the said partition, near its top. The lower deflector, when down or closed, inclines downward toward and rests upon the lower edge of the mouth a, and when raised upward to its highest position such deflector inclines upward toward and rests against the top of the said mouth.

Over the lower deflector are two movable rectangular plates, D and E, which are hinged together and extend across the hood. They are arranged at an acute angle to the lower deflector, to which the lower of said plates, at its lower edge, is hinged. At its upper edge the upper of the said plates bears against the front side of the partition b. The said up-

per plate extends under and against two studs, d d, projecting inward from opposite sides of the hood, and arranged as represented.

A rope or chain, c, is fixed to the upper part of the lower plate and extends upward and around guide-wheels f, g, and h, arranged within the hood in manner as represented, and is fastened to the upper deflector. From this latter deflector an arm, i, extends, as shown, and has attached to it, and to a stud, k, at the front of the hood, an elastic spring, l, which operates to pull forward the arm i and turn the upper deflector downward toward the partition.

In case of a sea entering the mouth of the ventilator when the deflector C is down, such sea will impinge against either or each of the plates D and E and force them downward, whereby the upper deflector will, at the same time, be raised to an inclined or closing position, so as to serve as a barrier to prevent the water from passing upward and over the top of the partition, and thence falling down through the hood. Immediately on the force of the sea becoming expended the upper deflector will be moved downward against the partition, and the two plates D and E will be drawn upward into one plane with each other by the retractive power of the spring, the two studs d d operating to prevent the upper of the plates from being drawn up higher.

In raising the deflector C the upper of the plates D and E will be borne against the studs, which will hold it down, while the lower plate moves upward with the said deflector. Thus it will be seen that the addition of the two plates D and E does not prevent the raising of the lower deflector up to the top of the mouth a.

I would remark that I do not herein claim the ventilator-hood provided with the single mouth, the partition, and the two movable deflectors, such having been the subject of or described in an application for a patent lately made by me.

What I claim as my invention is as follows:

1. The combination of the two plates D and

E, hinged to each other and arranged, as described, within the hood A, and connected with the upper deflector, B, by means as explained, with such deflector and its operative spring, 5 and the partition b, arranged in the hood, as set forth.

2. The combination of the studs d, with the

hood A, its partition b, and two deflectors B and C, and the plates D and E, arranged and applied substantially as explained.

PATRICK MIHAN.
